02-702
01406

AU EX
OR D 018,920

DESIGN.

C. A. GRISWOLD.

ORNAMENTATION OF CORSETS.

No. 18,920.

Patented Feb. 12, 1889.

WITNESSES:

C. W. Benjamin
C. S. F. Fales

INVENTOR

Catharine A. Griswold
BY Andrew S. Fales

ATTORNEY

UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 18,920, dated February 12, 1889.

Application filed January 4, 1889. Serial No. 295,474. Term of patent 14 years.

To all whom it may concern:

Be it known that I, CATHARINE A. GRISWOLD, of the city of New York, county and State of New York, and a citizen of the United States, have invented and produced a new and original Design for the Ornamentation of Corsets, of which the following is a full, clear, and exact description, reference being had to the accompanying drawing, forming part of this specification.

The single figure in the drawing represents a corset in side elevation containing my new design.

The leading and special feature of my new design consists in a band or stripe extending on the corset-surface from the lower edge thereof upwardly to and somewhat beyond the waist-line of the corset, and thence with an edgewise bend upon itself returning to and across said waist-line and downwardly to the said lower edge of the corset, together with a band or stripe extending on the corset-surface from the upper edge thereof downwardly to and somewhat beyond the waist-line of the corset, and thence with an edgewise bend upon itself returning to and across said waist-line and upwardly to the said upper edge of the corset, the described edgewise-bent portions of the said respective bands overlapping each other at and where they extend above and below said waist-line of the corset.

A represents a corset, which may be in the usual and ordinary form.

B' represents a band or stripe extending on the corset-surface from the lower edge thereof upwardly to and somewhat beyond the waist-line of the corset, and thence with an edge-wise bend, b', upon itself returning to and across said waist-line and downwardly to said lower edge of the corset.

B represents a band or stripe extending on the corset-surface from the upper edge thereof downwardly to and somewhat beyond the waist-line of the corset, and thence with an edgewise bend, b, upon itself returning to and across said waist-line and upwardly to said upper edge of the corset.

The edgewise-bent portions b and b' of the respective bands B and B' overlap each other where they meet at and as they extend above and below the waist-line of the corset.

What I claim is—

The design for the ornamentation of a corset herein described and shown, the same consisting in a band or stripe, B', extending on the corset A from the lower edge thereof upwardly to and somewhat beyond the waist-line thereof, and thence with an edgewise bend, b', upon itself returning to and across said waist-line and downwardly to said lower edge of the corset, together with a band or stripe, B, extending from the upper edge of the corset downwardly to and somewhat beyond the waist-line thereof, and thence with an edgewise bend, b, upon itself returning to and across said waist-line and upwardly to the said upper edge of the corset, the bent portions b and b' of said respective bands overlapping each other where they meet at and as they extend above and below the waist-line of the corset.

CATHARINE A. GRISWOLD.

Witnesses:

JOHN J. ENNIS,
A. S. FITCH.